DESIGN FOR A BOTTLE

William A. Nester, East St. Louis, Ill., assignor to Obear-Nester Glass Company, St. Louis, Mo., a corporation of Missouri

Application November 19, 1934, Serial No. 54,077

Term of patent 14 years

To all whom it may concern:

Be it known that I, William A. Nester, a citizen of the United States, residing at East St. Louis, county of St. Clair, Illinois, have invented a new, original, and ornamental Design for Bottle, of which the following is a specification and as substantially shown in the accompanying drawing, in which—

Fig. 1 is a plan view of a bottle embodying my new design.

Fig. 2 is a front elevation.

Fig. 3 is a side elevation.

Fig. 4 is a rear elevation.

I claim:

The ornamental design for a bottle substantially as shown.

WILLIAM A. NESTER.
